CLAIM

The ornamental design for a cover for the bed of a pickup truck, as shown.

DESCRIPTION

FIG. 1 is a side perspective view of a cover for the bed of a pickup truck with the rear deck in partially open condition showing our new design, it being understood that the broken lines are for illustrative purposes only; FIG. 2 is an enlarged side perspective view thereof in closed condition;

FIG. 3 is a rear perspective view of FIG. 2;

FIG. 4 is a front perspective view of FIG. 2;

FIG. 5 is a top plan view of FIG. 2; and

FIG. 6 is a bottom plan view of FIG. 2.
